UNITED STATES PATENT OFFICE.

NICHOLAS WITSCH, OF JERSEY CITY, NEW JERSEY, ASSIGNOR TO THE AMERICAN LITHOGRAPHIC COMPANY, OF NEW YORK, N. Y.

DESIGN FOR AN ORNAMENTAL PRINT FOR CIGAR-BOXES.

SPECIFICATION forming part of Design No. 25,302, dated March 31, 1896.

Application filed February 28, 1896. Serial No. 581,207. Term of patent 7 years.

To all whom it may concern:

Be it known that I, NICHOLAS WITSCH, a citizen of the United States, residing at Jersey City, in the county of Hudson and State 5 of New Jersey, have invented and produced a new and original Design for an Ornamental Print or Pattern for Cigar-Boxes; and I do hereby declare the following to be a full, clear, and exact description of the same, reference being had to the accompanying drawing, forming a part thereof.

The design is placed upon a cigar-box, as shown in the drawing, and consists of an oval panel surmounted by a crown and containing 15 an emblazoned symbol showing a lion rampant. The oval panel has an oblong rectangular panel in background and has a highly-ornamental border festooned above by a ribbon and flanked upon each side by fretwork.

I claim—

The design for an ornamental print or pattern for cigar-boxes, substantially as shown and described.

In testimony whereof I affix my signature in presence of two witnesses.

NICHOLAS WITSCH.
